UNITED STATES PATENT OFFICE.

HARRY MITCHELL KOENIG, OF MILWAUKEE, WISCONSIN.

FOUNTAIN PEN.

Application filed May 7, 1923. Serial No. 637,234.

To all whom it may concern:

Be it known that I, HARRY MITCHELL KOENIG, a citizen of the United States, and resident of Milwaukee, in the county of Milwaukee and State of Wisconsin, have invented new and useful Improvements in Fountain Pens, of which the following is a description, reference being had to the accompanying drawings, which are a part 10 of this specification.

This invention relates to fountain pens, and has for one of its objects to provide a pen of this character having an ink reservoir and a feed bar or other means wherein provision is made for cutting off or opening communication between the said feed bar and the reservoir at will, whereby when such communication is closed, leakage of ink from the pen will be wholly prevented.

20 A further object of the invention is to provide a pen of the class described having a relatively simple and effective valve for controlling communication between the ink reservoir and the feed bar.

25 A still further object of the invention is to provide a pen of the self-filling type having two separate ink chambers, communication between which is controlled by valves to the end that the flow of ink from 30 one chamber to the other may be readily controlled.

A still further object of the invention is to provide a pen which will not leak, while at the same time it will always be 35 ready to write.

A still further object of the invention is to provide a pen which will be simple in construction, relatively inexpensive to manufacture and more efficient in operation than 40 those which have been heretofore proposed.

With the above and other objects in view, which will appear as the description proceeds, the invention consists in the novel details of construction and combinations of 45 parts more fully hereinafter described and particularly pointed out in the appended claims.

50 Referring to the accompanying drawing, in which like numerals designate like parts in all the views;

Figure 1 is a central vertical sectional view, partly in elevation of a fountain pen, made in accordance with the present invention;

55 Fig. 2 is a view similar to Fig. 1, show-

ing the main ink reservoir collapsed for the purpose of filling the pen;

Fig. 3 is a horizontal cross-sectional view, taken approximately on the plane indicated by the line 3—3 in Fig. 1;

60

Fig. 4 is an enlarged detail sectional view of the lower portion of the pen barrel and the feed bar;

Fig. 5 is a horizontal cross-sectional view, taken approximately on the plane indicated by the line 5—5 in Fig. 4, showing the valve 65 in open position;

Fig. 6 is a view similar to Fig. 5, showing the valve in closed position; and,

Figs. 7 and 8 are fragmentary elevational 70 views of the lower portion of the pen, showing the positions of the parts with the valve respectively in closed and open positions.

Referring more particularly to the drawings, the numeral 10 indicates the hollow tubular barrel constituting the pen body, the upper end of which may be closed by a threaded plug 11 and the lower end of which is closed by a threaded plug member 80 12. The member 12 is provided at its upper end with a reduced portion 13, which is adapted to receive the lower open end 14 of the rubber or other resilient collapsible tube 15. The upper end of the said tube 15 is 85 closed, as indicated in Figs. 1 and 2, and the said tube constitutes the main ink reservoir, as is well known in this type of pen.

The upper end of the plug member 12 is further reduced above the portion 13, as 90 indicated at 16, and carries a suitable valve cap member 17, provided with a valve opening or port 18, see Figs. 4, 5 and 6. The said cap member 17 also serves to reinforce the upper reduced end 16 of the plug member 12 and tends to reduce the possibilities of the said reduced end being broken off should the ink in the reservoir member 15 become exhausted, thereby permitting such ink as might remain in the duct or passage 100 21 to dry and cement the feed bar 20 to plug member.

The plug member 12 is further provided with an axial bore 19, extending therethrough, in which is mounted the oscillatory feed bar 20, provided with the feed duct 21, see Fig. 4. The said feed bar 20 is rigid with the lower finger member 22 by means of which it may be oscillated within the bore 19 to move the upper end of the 105 110 feed bar 20 to plug member.

duct 21 into and out of register with the valve port 18, whereby communication may be controlled between the tube 15 and the duct 21, as will be readily apparent. The member 22 is threaded upon the lower end of the plug member 12, as indicated at 23, thereby serving to retain the feed bar in place and the said members, 12 and 22, are provided with indentations or marks, 24 and 25 respectively, which are adapted to indicate the position of the duct 21, relative to the valve port 18. That is, when the two marks 24 and 25 are in alignment, as indicated in Fig. 8; a reinforcing cap member 15 carried by one end of said plug and the duct 21 is in register with the port 18, thereby opening communication from the tube or chamber 15 to the said duct. However, when the marks 24 and 25 are out of alignment, as indicated at Fig. 7, the user will know that the duct 21 is out of register with the port 18, and that communication is closed off.

Any suitable means for collapsing the tube 15 may be provided, although the mechanism illustrated in Figs. 1, 2 and 3 of the present drawings is preferred. This said mechanism comprises a downwardly extending rod member 26, rigidly carried 30 by the upper plug member 11, in engagement with one side of the tube 15. A companion rod member 27 is slidably mounted in the said plug member 11, as will be clear from Figs. 1 and 2, and extends downwardly 35 along the opposite side of the said tube member. The two rod members, 26 and 27, are connected together by means of suitable links 28, so that when the member 27 is depressed it will move downwardly and be 40 drawn towards the member 26, by the said links, to compress the tube 15 and expel the air therefrom, in the well known manner. Of course, if the pen point 29 is immersed 45 in ink at this point and the member 27 released upon expansion of the tube 15, the ink will be drawn up into the said tube, as will be readily understood. Of course, the member 22 should be adjusted during such filling operation so that the duct 21 registers 50 with the valve port 18, in order to permit the ink to enter the tube 15.

The upper end of the rod member 27 is provided with an enlarged head 30, beneath which is placed a coiled spring 31, seated 55 in a counter-bore 32, with which the plug member 11 is provided. The said spring 31 will normally urge the rod member 27 upwardly, thereby permitting the tube 15 to maintain its normally expanded position. A readily removable cap member 33 may be 60 threaded upon the upper end of the plug member 11 to seal and protect the head 30 and spring 31, as will be readily understood, when these members are not in use for the 65 purpose of filling the ink reservoir.

While the invention has been illustrated and described in connection with a self-filling pen, it will be obvious that if desired it may be applied with equal facility to a pen not provided with a self-filling mechanism. It will also be apparent that the invention provides a pen having two chambers, one comprising the tube or reservoir 15, and the other comprising the duct 21, communication between which is controlled by the 75 valve port 18.

If, after using the pen, the feed bar 20 is rotated by means of the member 22, to bring the duct 21 out of register with the port 18 before the pen is inverted, ink will be 80 trapped in the duct or chamber 21 and will maintain the point of the pen wet, thereby facilitating easy writing of the pen when again used. On the other hand, should the pen be inverted before the duct 21 is moved 85 out of register with the port 18, then such ink as was in the said duct will flow back into the tube or reservoir 15, and after the valve is closed it will be impossible for ink to leak out of the said reservoir.

The flow of ink from the main reservoir 15 to the pen point may also be controlled by adjusting the position of the duct 21 relative to the port 18. Should the ink flow too freely from the said reservoir when the said port is fully opened, it is only necessary to move the member 22 slightly to partially close the valve, whereupon the flow of ink will be reduced the desired extent.

While one form of the invention has been illustrated and described it is obvious that those skilled in the art may vary the details of construction as well as the arrangement of parts without departing from the spirit of the invention, and therefore it is not wished to be limited to the above disclosure except as may be required by the accompanying claims.

What is claimed is:

1. A fountain pen comprising an ink reservoir; a plug member closing one end of said reservoir; a reinforcing cap member carried by one end of said plug and provided with a port communicating with said reservoir; a pen point and a feed bar mounted for oscillatory movement in said plug member, said bar having a duct adapted to register with said port; and a finger threaded on the other end of said plug member, and rigid with said bar for oscillating the latter.

2. A fountain pen comprising a barrel; a collapsible ink reservoir within said barrel; a plug member secured in one end of said barrel and closing one end of said reservoir, said plug member being provided with an axial bore and with a reinforcing cap member on one end having a port providing communication between said reservoir and said bore; a feed bar mounted for oscillation in said bore, provided with a

duct adapted to be moved into and out of register with said port; a pen point associated with said feed bar; and a finger member detachably carried by said plug member for oscillating said feed bar.

3. A fountain pen comprising a barrel; a collapsible ink reservoir within said barrel; a plug member secured in one end of said barrel, having a reduced portion entering one end of said reservoir, said plug also having a substantially axial bore; a cap carried by said reduced portion of said plug member, provided with a port afford-

ing communication between said reservoir and said bore; a feed bar mounted for oscillation in said bore, provided with a duct adapted to be moved into and out of register with said port; a pen point associated with said feed bar; means carried by said plug member for oscillating said feed bar; and means carried by said oscillating means and said plug member for indicating the position of said duct relative to said port. 15

In testimony whereof, I affix my signature.

HARRY MITCHELL KOENIG.
